UNITED STATES PATENT OFFICE.

OSCAR E. BROWN, OF LANCASTER, PENNSYLVANIA.

VALVE GRINDER.

Application filed December 24, 1919. Serial No. 347,124.

To all whom it may concern:

Be it known that I, OSCAR E. BROWN, a citizen of the United States, residing at Lancaster, in the county of Lancaster, State of Pennsylvania, have invented certain new and useful Improvements in Valve Grinders; and I do hereby declare the following to be a full, clear, and exact description of the invention, such as will enable others skilled in the art to which it appertains to make and use the same.

This invention relates to tools for grinding metal, and more particularly to those adapted for grinding curved surfaces; and the object of the same is to produce a grinder for the valves and seats of automobile engines, having special means for adapting it for use on various makes and types of engines.

The primary feature of the invention is the means which imparts to the valve an oscillatory motion through successively varying arcs, combined with a reciprocating movement of the valve so that it does not at all times rest upon its seat. A feature of the invention lies also in means for adjusting the movements of the tool to adapt it to different conditions.

Another feature of the invention is a support with means for adapting it to different makes of engines.

Details are set forth below and are shown in the drawings wherein:

Figure 1 is a vertical section through this tool complete.

Figure 2 is an elevation of this tool with the face plate and driving mechanism removed, certain parts being in section.

Figure 3 is an inside elevation of the driving gear and cam.

The body 1 of this tool is upright and hollow, one side being ring shaped and open as seen in Figure 2, and closed by a face plate 2 held in place by fastening means which may be removed to gain access to the interior mechanism. At the upper end of the body is a handle 3. To the lower end of the body is connected a support 4 preferably having a plurality of legs 5 at its lower end spaced to permit inspection of the work being done, and a pair of arms 6 at its upper end which pass astride the body and are slotted as at 7 to be engaged by set screws 8 so that the support may be adjusted vertically for different types of engines. For some engines wherein the valves are large the legs can be

spread and for this purpose the outfit will be provided with several extensions 5' capable of being interchangeably attached to the legs in any suitable way, as by slots and set screws 9 or otherwise. The purpose of this support is to maintain the tool in upright position and in strict axial alinement with the valve and its seat at all times, the operator being required only to grasp the handle 3 in one hand and bear downward.

Mounted for rotation and reciprocation within the body is the main shaft whose upper portion 10 rises into the handle and is borne normally downward by means of an expansive spring 11 therein, while its lower portion is tubular as indicated at 12 to receive an extension shaft or spindle 13, the same being adjustable by means of a set screw 14. In other words, the main shaft is in two parts telescopically connected so that it can be lengthened or shortened, and the lower part or spindle 13 carries any one of a number of bits 15 which are adapted to the valves of various types of engines. For this purpose the lower end of the spindle is slotted and the bit passed upward into the slot and held there by a screw 16. It will be understood without further illustration that the bit engages the nick or nicks in the top of the valve while the latter rests on its seat, and in the act of grinding, an abrasive composition is placed between the seat and valve so that when the latter is depressed against its spring and turned, the faces are ground. It is clear that if the oscillation of the valve is through a single arc, the grinding composition may cut grooves in said faces which would destroy the efficiency of the valve, and therefore means are present for varying the arcs of oscillation and for raising and lowering the valve between strokes as will be explained.

Journaled through the center of the face plate 2 is a power shaft 20 squared at its outer end to engage a slot 21 within a crank handle 22 which has a hand piece 23, and a screw 24 passes through the slot and into the end of the shaft whereby the crank may be adjusted with respect to its operative length to suit the wishes of the user. Fast on the shaft 20 next inside the face plate is a power gear 25 whose teeth are mutilated through more than half the distance around its periphery as indicated at 26; and fast on the shaft 20 next inside this gear is a cam 27, the cam standing along-

side the upper portion 10 of the main shaft. When the face plate is removed from the body, the power gear and cam come off with it.

5 Secured to the main shaft as by a set screw 38 is a collar 39 which is engaged by the cam at each revolution to raise this shaft against the tension of the spring 11. Splined on the shaft above this collar is a 10 driven gear 36 adapted to be engaged by the teeth at the upper side of the power gear, and splined on the shaft at some distance below the collar is another driven gear 37 adapted to be engaged by the teeth 15 at the lower side of the power gear. The hubs of these gears at their outer ends may rest against shoulders 30 which are cast as parts of the body, while their inner ends may be held by forks 31 on a bracket secured 20 within the body and having their arms passing astride the shaft—therefore the gears may not move longitudinally during the reciprocations of the shaft under the impulses of the cam, but the shaft will 25 be rotated by the gears because they are splined upon it, and the gears will of course be successively rotated as their teeth engage those upon the power gear 25. Each gear is preferably splined to the shaft by 30 means of a set screw 32 passing through its hub and engaging a longitudinal groove 33 cut in the shaft, and by preference I provide several such grooves 34 of different length with which the set screw of the 35 lower gear 37 may be engaged at will.

In operation, the arms of the support are adjusted alongside the lower end of the body and the main shaft is adjusted in length to adapt the tool to the engine on 40 which it is to work. The valve cap is removed, and a proper bit 15 applied and engaged with the nick of the valve, the support being stood upon the head of the cylinder and held upright by the operator 45 who grasps the handle 3 with his left hand. Now he grasps the crank handle 23 with his right hand and imparts rotary motion to the power shaft 20, and at each revolution thereof the teeth of the power gear engage first one driven gear and then the other. Because said power teeth extend less than half way around the power gear, the oscillation given to the main shaft will be 50 through arcs varying in length, as will be clearly understood, that gear which is opposite the mutilation 26 turning backward during the impulse being imparted to the other gear by the power teeth. Meanwhile also the cam 27 intermittently raises the lower shaft by its engagement beneath the collar 39. This permits the valve to rise off its seat for an interval, although the oscillatory motion described is not interrupted; and therefore the combination of the oscillatory and reciprocatory movements will 60

produce a variety of arcs through which the effective grinding operation is performed. By loosening the set screw 32 and setting it into one of the other grooves 34, the amplitude of the reciprocations can be 70 varied to accommodate certain types of machines and the wishes of certain operators. The fact that the main shaft rises and falls at intervals makes the use of some support imperative and as such support I prefer to employ that herein shown and described. However, if the cam be removed from the power shaft, the reciprocations of the main shaft cease while its oscillations through 75 various arcs continue.

Obviously the extent of the rearward or upward movement of the shaft which carries the valve holder is due to the angular movement described by the cam while in contact with the shoulder formed on the 80 said shaft by the sleeve or collar 38, and that by limiting the movement of the shaft in a forward or downward direction, through the agency of the cooperating set screw 32, and grooves 34, the terminal position of the shoulder with relation to the axis of the cam may be varied to provide for a greater or lesser throw, as may be required in the particular work to be performed. It will further be obvious that 85 in making such adjustments the engagement of the set screw 32, with different grooves 34, or grooves having different lengths, or permitting different throws of the shaft, a corresponding adjustment of the foot piece 90 or support 4, must be effected through the agency of the slots 7, and engaging set screws 8, or by means of the feet 5, which are employed as above described in connection with the legs of the support or foot 95 piece to adapt the apparatus to cylinders having different diameters or valve ports.

What is claimed as new is:

1. In a valve grinder, the combination with a hollow body, a driven gear rotatably mounted therein, and means for oscillating it irregularly; of a shaft mounted for rotation and reciprocation in said body and extending through the gear, the shaft having a plurality of grooves of various lengths, means in the gear for engagement with the grooves selectively to limit the descent of the shaft, a spring bearing the shaft normally downward, and valve-holding means at its lower end.

2. A valve grinder comprising a frame, a shaft mounted for oscillation and reciprocation in the frame and having means for connection with a valve to be ground, means for oscillating the shaft, means for reciprocating the shaft and means for varying the extent of the reciprocation of the shaft.

3. A valve grinder comprising a casing, a shaft mounted in the casing for oscillation and reciprocation and having means for con-

nection with a valve to be ground, means for oscillating the shaft, means for reciprocating the shaft between the reverse movements of its oscillations and means for varying the extent of the reciprocation of the shaft.

4. In a valve grinder, the combination with a body having a hollow intermediate portion with shoulders at the upper and lower ends thereof, a shaft mounted for oscillation and reciprocation in the body and extending across its hollow portion, valve-carrying means at the lower end of the shaft, yielding means at its upper end bearing it normally downward, and a driving shaft journaled in one side of the body, of a mutilated driving gear on the driving shaft, driven gears splined on the main shaft in contact with said shoulders and successively engaged by the teeth of said mutilated gear, a bracket within said hollow portion having forks engaging the inner ends of the driven gears, and connections between the shafts for raising the main shaft at intervals.
5. A valve grinder having a stand and a shaft mounted for rotary and reciprocatory movement and carrying valve holding means, a driven gear through which said shaft extends and to which it is keyed by means determining a variable limit of movement toward the valve seat, the shaft being yieldingly impelled toward the seat, and gear actuating means having a shaft lifting cam for engagement with a shoulder on the shaft.
6. A valve grinder having a casing extended radially to form diametrically registering tubular guides, a shaft mounted in said guides and extending beyond one of

them to carry the valve holder, a grip seated in the other guide, a rest exteriorly fitted upon the first named guide for bearing contact with a cylinder head, and means housed in the casing for actuating the shaft.

7. A valve grinder having a casing extended radially to form diametrically registering tubular guides, a shaft mounted in said guides and extending beyond one of them to carry the valve holder, a grip seated in the other guide, a rest exteriorly fitted upon the first named guide for bearing contact with a cylinder head, means housed in the casing for actuating the shaft, and the grip being axially bored in alignment with the shaft, and a shaft impelling spring being arranged in said bore in permanent contact with the shaft.

8. A valve grinder having a casing extended radially to form diametrically registering tubular guides, a shaft mounted in said guides and extending beyond one of them to carry the valve holder, a grip seated in the other guide, a rest exteriorly fitted upon the first named guide for bearing contact with a cylinder head, means housed in the casing for actuating the shaft, and a support or foot piece being axially adjustable upon the guide upon which it is fitted and having slots engaged by set screws to secure the same in adjusted relation with the path of movement of the shaft.

In testimony whereof, I affix my signature, in the presence of two witnesses.

OSCAR E. BROWN.
